UNITED STATES PATENT OFFICE.

FRED W. WILMOT, OF LONG BEACH, CALIFORNIA.

RIM MOUNTING.

Application filed February 24, 1926. Serial No. 90,372.

This invention relates to improvements in rim mountings, and has particular reference to a mounting for use with demountable rims, commonly employed in securing automobile tires upon wheels.

The principal object of this invention is to provide means which will securely hold the demountable rim upon the steel felly of the wheel and assist in the proper centering 10 of the rim without a wedging action of the device.

Another object is to produce a device of this character which will prevent distortion or bending of the wheel holding bolt.

An additional object is to produce a device 15 of this character which may be employed with any form of demountable rim wheel employing bolts, which is now upon the market, without materially altering the construction of the same.

A still further object is to produce a device which is economical to manufacture and one which may, therefore, be readily applied.

Other objects and advantages will be 25 apparent during the course of the following description.

In the accompanying drawings forming a part of this specification, and in which like numerals are employed to designate like 30 parts throughout the same,

Figure I is a fragmentary cross section of a steel felly and rim attached thereto, employing my device,

Figure II is a side elevation of the bolt 35 engaging cam,

Figure III is a side elevation of the cam and rim engaging member, and

Figure IV is a front elevation of Figure III.

At the present time, it is common to 40 employ merely a bolt extending through the felly over which a locking member is placed, which locking member is tightened against the rim, through the medium of the usual nut, screwed upon the bolt. I have sought to improve this rim engaging means by providing a new form of clamp, wherein the rim will be more perfectly centered upon the wheel.

In the accompanying drawings wherein 50 for the purpose of illustration is shown a preferred embodiment of my invention, the numeral 5 designates the customary steel

felly of a wheel having a flange 6 against which a portion of the demountable rim 7 is adapted to contact.

The flange 8 of the felly 5 is of lesser diameter than the flange 6 and, therefore, clears the inner periphery of the rim 7. This permits the rim to be slipped over the 69 felly.

At 9 I have shown a bolt having a squared portion 11 which prevents the bolt from rotating. It is, of course, understood that the squared portion fits in a squared opening 65 formed in the felly. This bolt passes through the felly and is adapted to have screwed thereon a bolt-engaging cam 12. This cam has a reduced portion 13, which enters the hole in the felly through which the 70 bolt passes.

This serves to center the bolt and, therefore, hold the same steady. The cam surface 14 is adapted to be engaged by the cam surface 16 of the rim-engaging member 17. 75 This rim-engaging member has an opening 18 formed therein, which opening passes over the bolt 9 and is provided with a rim-engaging surface 19, while upon its opposite side is provided a nose 21 which is adapted 80 to contact the felly.

The result of this construction is that as the nut 22 is tightened upon the bolt 9, the rim engaging member 17 will engage the rim 7, while the nose will contact the felly. Continued tightening of the nut 22 will 85 cause the member 17 to ride upon the cam surface 14 assisting in the centering of the rim upon the felly.

This cam member 12 taken with the rim engaging member 17 provides an additional strength to the bolt, thereby relieving the bolt of the bending or weaving action which would be commonly transmitted from the rod to the felly therethrough.

It will thus be seen that I have produced a very simple device which will accomplish all of the objects above set forth.

It is to be understood that the form of 100 my invention herewith shown and described is to be taken as a preferred example of the same, and that various changes in the shape, size and arrangement of parts may be resorted to without departing from the spirit 105 of the invention or the scope of the subjoined claims.

Having thus described my invention, I claim:

1. In combination with a felly having a bolt extending therethrough, a cam member 5 threadedly secured on said bolt and having a portion thereof engaging said felly, a rim-engaging member slidably positioned on said bolt, a cam surface formed in said rim-engaging member and adapted to engage the cam surface of said cam member, a nose 10 adapted to engage the felly, and a rim-contacting surface formed thereon.
2. In combination with a felly and a rim therefor, a bolt passing through said felly 15 and having a square part fitting a square opening in the felly, a bolt engaging cam threadedly secured to said bolt and having a reduced portion formed on one end for entering a bolt hole in the felly to center 20 said bolt, a cam surface formed on the opposite side, and means received by said bolt and

formed with a cam surface to cooperate with the cam surface first mentioned to arrange the rim upon the felly and a nut for said bolt to engage said means. 25

3. In combination with a felly and a rim, a bolt passing through said felly and having a square part fitting a square opening in the felly, a bolt engaging cam threadedly secured to said bolt and having a reduced portion formed on one side thereof for entering a bolt hole in the felly to center the bolt, a cam surface formed on the opposite side of said bolt engaging cam, a member received by said bolt and having a cam surface 30 cooperating with the cam surface first mentioned to center the rim upon the felly, a rim engaging member on the member first mentioned, and a nose also on said first mentioned member to contact the felly. 35

In testimony whereof I affix my signature.

FRED W. WILMOT. 40
